UNITED STATES PATENT OFFICE.

FREDERICK B. RISING, OF ANTRIM, NEW HAMPSHIRE, ASSIGNOR TO THE GOODELL COMPANY, OF SAME PLACE.

DESIGN FOR A FRAME FOR FRUIT OR VEGETABLE PARERS.

SPECIFICATION forming part of Design No. 28,705, dated May 24, 1898.

Application filed April 23, 1898. Serial No. 678,671. Term of patent 14 years.

To all whom it may concern:

Be it known that I, FREDERICK B. RISING, a citizen of the United States, residing at Antrim, in the county of Hillsborough, State of New Hampshire, have invented and produced 5 a new and original Design for a Frame for Fruit or Vegetable Parers, of which the following is a specification.

Figure 1 is a side elevation of a frame for 10 fruit and vegetable parers, illustrating my design; and Fig. 2 is a right-hand edge elevation thereof.

The leading feature of my design for a frame for fruit and vegetable parers comprises a body bent in the direction of its length 15 and having a laterally-offset head provided with a curved ear and a hub, a longitudinal rib on the upper portion of the body, having a stand projected therefrom, and an ear at its 20 upper end opposite and parallel to a similar ear on the body at the base of the head. The body is enlarged below the head and provided with an annular rib and an adjacent projecting arm, a recess in the body extending in- 25 ward from the edge thereof above the annular rib. At the bend in the body a lateral arm projects, having an upturned extremity opposite the lower end of the longitudinal rib.

The body comprises upper and lower por- 30 tions A A', bent at about the point A^X, Fig. 2, at which point projects a lateral arm a, having an upturned extremity a', which is op- posite the lower end of a longitudinal rib b

along one edge of the part A of the body, said rib having at its upper end a projecting ear 35 b' and near its lower end a projecting stand b², both the ear and the stand being in the plane of the rib and substantially at right angles to the adjacent body portion A, which latter has a laterally-offset and substantially 40 scroll-shaped head A², provided at its extremity with a curved ear a² and having a hub a³. An ear a⁴ is extended at right angles from the upper end of the body portion A similar to and in parallelism with the ear b'. The 45 upper end of the body portion A is enlarged, as at A³, and is provided on its face with an annular rib a⁵, while a recess a⁶ extends inward from the edge of the enlarged portion above the annular rib and below the ear a⁴, 50 an arm a⁷ projecting from the part A³ of the body below the ear a⁴, the said arm being set at an angle to the face of the body A.

Having fully described my design, what I claim, and desire to secure by Letters Patent, 55 is—

The design for a frame for fruit and vegetable parers, substantially as shown and described.

In testimony whereof I have signed my 60 name to this specification in the presence of two subscribing witnesses.

FREDERICK B. RISING.
